(57) **CLAIM**

The ornamental design for a storage panel and bracket, as shown and described.

DESCRIPTION

FIG. 1 is a front perspective view of the storage panel and bracket;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken lines in the drawings illustrate portions of the storage panel and bracket that form no part of the claimed design.
